DESIGN FOR A COMBINED SOLE AND HEEL

Leon C. Martel, Providence, R. I., assignor to National India Rubber Company, Bristol, R. I., a corporation of Rhode Island

Application May 12, 1934, Serial No. 51,757

Term of patent 14 years

To all whom it may concern:

Be it known that I, LEON C. MARTEL, a citizen of the United States of America, residing at 355 Valley Street, city of Providence, county of Providence, State of Rhode Island, have invented a new, original, and ornamental Design for a Combined Sole and Heel, of which the following is a specification, reference being had to the accompanying drawing, forming part thereof, in which:

Fig. 1 is a plan view of a combined sole and heel showing my new design; and

Fig. 2 is a sectional elevation taken on line 2—2 of Fig. 1.

I claim:

The ornamental design for a combined sole and heel, as shown.

Signed at Providence, county of Providence, State of Rhode Island, this 9 day of May 1934.

LEON C. MARTEL.
